United States Patent Office

Des. 205,337
Patented July 19, 1966

205,337

SPRAY HEAD

Garland L. Sheldall, Los Angeles County, Calif.
(9063 Nagle Ave., Panorama, Calif.)

Filed Oct. 24, 1965, Ser. No. 87,899

Term of patent 14 years

(Cl. D91—3)

FIG. 3FIG. 4FIG. 6

The broken lines are for illustrative purposes only.

I claim:

The ornamental design for a spray head, substantially as shown and described.
